(57) **CLAIM**

The ornamental design for an automatic printing machine, as shown and described.

DESCRIPTION

FIG. 1 is a front view showing our new design for an automatic printing machine;

FIG. 2 is a rear view of the automatic printing machine of FIG. 1;

FIG. 3 is a right side view of the automatic printing machine of FIG. 1;

FIG. 4 is a left side view of the automatic printing machine of FIG. 1;

FIG. 5 is a top view of the automatic printing machine of FIG. 1;

FIG. 6 is a bottom view of the automatic printing machine of FIG. 1;

FIG. 7 is a perspective view of the automatic printing machine of FIG. 1;

FIG. 8 is an enlarged front view of the portion of the automatic printing machine of FIG. 1 above the line 8—8; and,

FIG. 9 is an enlarged perspective view of the portion of the automatic printing machine of FIG. 8.
